PORTABLE FOUNDATION WALL FORM

Richard R. von Bampus, Ringwood, Ill.

Application April 29, 1948, Serial No. 23,962

1 Claim. (Cl. 25—131)

1

This invention relates to a portable foundation form, and particularly to a detachable foundation casting form capable of being taken apart and transported to a given location and there set up for pouring a concrete foundation.

An important object of the invention is to provide a foundation casting or pouring form which is adapted to be used repeatedly for pouring any number of concrete foundations.

Another object is to provide an adjustable foundation form of the indicated character adapted to be used for making various sizes and shapes of foundations of cementitious materials.

A further object is to have such a foundation form which has facilities for stripping the forms or form sections from the foundation and leaving the latter in such excellent condition that the exterior surfaces thereof may be used without further treatment.

It is even an object of this invention to have a portable foundation form mounted on a group of supporting wheels allowing the entire form to be rolled from one foundation or basement, from which the form sections have just been stripped, to a nearby site for the next foundation or basement to be poured without dismantling the apparatus.

It is also an object to provide a foundation form of this type having facilities for preventing distortion of the resulting foundation out of true or square-cornered form.

It is likewise an object to have a foundation form which requires a minimum of labor for handling the same and which is readily adjustable in location to set it into accurate position.

Other objects and specific features of the invention will become apparent from the following description when considered in connection with the accompanying drawings, in which:

Figure 1 is a plan view of portable foundation form made according to the invention and embodying the same in a practical form, parts being broken away to reduce the view;

Figure 2 is a side elevation of the same foundation form as seen from the right in Figure 1;

Figure 3 is a transverse section of a foundation wall made by the pouring or casting form of the invention and showing portions thereof in position on both sides of the wall, the latter being enlarged to better disclose detail;

Figure 4 is a similar section of the foundation wall showing the form sections removed and apertures in the wall filled to complete the same;

Figure 5 is a side elevation of a tie rod;

Figure 6 is a vertical section through the foun-

2

dation wall at a point where a door frame appears, it being an enlarged vertical section on line 6—6 of Figure 8;

Figure 7 is a fragmentary plan view of the foundation as seen from the top and illustrating a door frame and a window frame in position in said foundation;

Figure 8 is a front elevation of the same fragmentary portion of the foundation showing the door and window frames in position;

Figure 9 is an enlarged fragmentary transverse section taken on line 9—9 in Figure 8;

Figure 10 is a fragmentary view of detail concerning the form sections and a tie rod holding the same together;

Figure 11 is an enlarged section taken on line 11—11 in Figure 1;

Figure 12 is a fragmentary perspective view of a modification of the form of invention shown in Figure 1;

Figure 13 is an enlarged vertical section taken on line 13—13 in Figure 12; and

Figure 14 is a fragmentary side elevation of the metal frame of Figure 13.

Throughout the various views, the same reference numerals indicate the same or like parts.

In the building industry, several formidable problems confront the builder, especially if he contemplates building a number of houses or other structure upon concrete foundations. Even though the latter may be of the shallow type or buildings which have no cellars or basements, the matter of providing proper forms for pouring concrete to make the foundations has always presented a considerable problem which yet remains to be solved.

The first problem is the cost of the forms. This is often prohibitive if the buildings to be erected are all different. In case several houses or other buildings are to be substantially the same in form, as far as the foundation is concerned, it sometimes does pay to make a set of forms suitable therefor. Especially would it be plausible to have forms for a large number of houses or

buildings which will have substantially the same type of foundation, even though they may vary in over-all dimensions, so long as they are relatively free from offsets and other irregularities.

After carefully considering this problem and others related to the same, I have found it quite feasible to design a special foundation form which is both adjustable and portable, as well as readily detachable from the foundation when the concrete or other cementitious material has set suf-

ficiently to stand without support, as will now be set forth in detail.

Hence, in the practice of my invention, and referring again to the drawings, a carrier frame, generally indicated at 15, consists of four corner structures 16, 17, 18 and 19. Each corner structure is carried by a pair of wheels 20, 21. These wheels are mounted on a shaft 22 which is carried in a frame structure 23. The frame structure pivotally and steerable supports the projecting end 24 of a frame member 25 which is preferably an I-beam or the like. The wheel assembly 20, 21, 22 and 23 is spaced sufficiently below the beam extension 24 to allow swiveling of the assembly for steering when the carrier frame is to be rolled to another excavation. The steering is effected by maneuvering the wheels. At right angles to the I-beam 25 is connected a second I-beam 26 by means of angle plates 27, 28 which are welded to beam 25, but riveted or screwed or otherwise releasably secured to the I-beam 26, as at 29 for example.

In similar fashion, the corner section 16 includes the two beams 30, 31; the corner section 17, the beams 32, 33, and corner section 18, the two beams 34, 35. All of the corner beams are secured together in a fashion similar to beams 25 and 26 of the corner section 19. In the corner sections 16, 17 and 18, the beams 30, 32 and 34 project beyond their correspondingly associated beams 31, 33 and 35. The projections 36, 37 and 38 are supported by their associated wheels 20 and 21 in each case. Four sets of wheels result, one at each corner, and together support the entire frame 15. In order to connect the mentioned corner sections together to form a coherent frame, the two beams 26 and 33 of corner sections 19 and 17, for example, are secured together by inside and outside channel members 39, 39, as best shown in Figure 11. Equidistantly spaced detachable bolts 40, 40 are used to secure the channel members in place in such fashion that the I-beams 26 and 33 may either meet at their common junction indicated at 41, or be spaced apart various distances according to a multiple of one of the distances between any two of bolts 40. In similar fashion, the two beams 30 and 32 of corner sections 16 and 17 are detachably secured together. They may either meet as shown at the intermediate junction 42 or be separated at stepped distances. The construction referring to the connection between the above-mentioned beams 26, 33 and beams 30, 32, also holds for the beams 31, 35 interconnected across their common junction 43 and for the beams 34, 25 connected across their intermediate junction 44. Although the holes in the beams are not shown, they are readily understood upon inspection of Figure 2 which shows the spacing of bolts 40. The latter pass not only through the channel members 39, 39, but also beams 26 and 33. In similar fashion, inner and outer channels connect the other beams 30 and 32, 31 and 35 and 34 and 25. The frame just described is shown as occupying a minimum area. It may be made larger as desired by releasing bolts 40, 40 on opposite sides of the carrier frame and extending the beams. When the beams have been separated to the desired positions, the bridging channels are locked to the beams by tightening the bolts. In this way, the frame may be made longer, wider, or both. By such adjustments, various sizes of foundations may be built. The size of the carrier frame is limited only by the strength of its

individual members required to support the foundation form and by a consideration of portability.

In order to accommodate a pair of nested inner and outer form sections, each corner section of the carrier frame is provided with a supporting tower generally indicated at 45, 46, 47 and 48. Each tower is a trapezoidally-formed frame consisting of four I-beams welded together and disposed obliquely on the two beams of the respectively associated corner sections of the carrier frame. Thus, the tower 48, for example, includes the lower relatively long horizontal beam 49 secured by angle plates 50, 51 to beams 25 and 26, the inclined upwardly-directed side beams 52, 53 surmounted by the short horizontal beam 54, and an exterior inclined supporting beam 55 secured at its upper end to beam 54 and at its lower end to beams 25 and 26 by angle plates 56 and 57.

Preferably, the towers are reinforced at their lower corners by plates 58 and 59, etc., welded to horizontal beam 49 and post 52 and similar plates 60, 61 welded to the same horizontal beam 49 and post 53. At its upper end, the supporting beam 55 is secured to the horizontal short beam 54 by means of angle plates 62, 63. Suspended from each of the upper beams on the four towers, as for example from beam 54, is a chain hoist including a block 64 with a chain 65 terminating in a hook 66. As the other three towers are exactly the same in all details, the references applied to the tower generally indicated at 48 may be considered as also applying to each of the towers 45, 46 and 47.

The mentioned hook 66 of the tackle block 64 suspended at 67 from the upper horizontal beam 54 engages in an eye member 68 of a radially-directed carrier bar 69 which is releasably secured at the upper corners of an inner form 70 and an outer form 71. The inner form 70 includes a group of panel sections 72, 72 forming one side of the form and groups of similar panel sections 73, 74 and 75 constituting the other three sides of the same form. The two corner sections 76, 77 are preferably permanently secured together and reinforced by a triangular plate 78 and the plate in turn is directly secured to the mentioned supporting bar. The other corners of the form are similarly constructed. Before discussing the details of each of the sections 72, 73, 74 and 75 of the inner form, it may be mentioned that the outer form 71 likewise consists of similar panel sections 79, 80, 81 and 82, and corner sections 83, 84. Carrier bars 85, 86, 87, corresponding to the bar 69, are similarly supported by tackle from the upper portions of towers 45, 46 and 47, as just described in connection with tower 48.

Each of the panel sections 72, 73, 74 and 75 of the inner form 70 are similarly formed. As shown in Figures 1 and 3, each panel includes a lower horizontal angle bar 88, an upper horizontal angle iron 89, a plurality of intermediate spaced upright angle members 90, 90 and at the ends similar angle members 91, 92. The end angle members 92 are secured to the next adjacent end angle member of the next section at 91 by means of bolts 93, 93. To the inside face of each panel section is secured a panel 94 of suitable material, for direct contact with concrete, such as waterproof plywood, plastic, or light sheet metal like aluminum. In similar fashion, the outer form 71 includes a series of panel sections 79 as already mentioned and

shown in larger detail in Figure 3. Each section includes a lower horizontal angle member 95, a similar upper horizontal angle member 96, and intermediately spaced upright angle members 97, 97. The end angle members 98 and 99 of adjacent panel sections are secured together by bolts 100, 100. Each group of angle members 97, 98, and 99 with lower and upper angle members 95, 96 thus constitutes a metal frame to which is secured on its inner face a panel 101 by means of screws or the like, not shown. This panel is similar to panel 94 which is provided on each section of the inner form 70. Variations in the construction of these panels are, of course, possible so long as the necessary reinforcement is provided.

It will be apparent from the above description that the forms 70 and 71 may be reduced or increased in size by the removal or the addition of panels. By so doing, walls of smaller or greater circumference may be built. Provision of shorter or longer carrier bars and tie rods will likewise provide for different wall thicknesses.

As best seen in Figures 2, 3 and 10, each panel has a group of tie rods thrust through the same and which extends from the outer form panels to and through the inner form panels. That is, they extend from panels of form 71 through the panels of form 70. This is effected by the provision of a plurality of apertures in the upright angle members 97, 98, 99 and 90, 91, 92. Through the mentioned apertures 102, 102 are inserted tie rods 103, 103, there being sufficient rods provided in each form section or panel to insure the maintenance of the space between the forms and eliminate bulging when the concrete is poured. Each rod is inserted up to its head 104 engaging against the angle member 97, for example, while upon the far side, that is, through the form panel 72, beyond the side of the opposite upright angle member 90, a pin 105 is fitted into a hole 106 in the tie rod. The tie rod also has a further hole spaced a distance beyond aperture 106 at 107 for inserting a tool and gaining purchase sufficient to force the opposite panels on the inner and outer forms toward each other to permit easy insertion of the pin 105. It may be noted that in view of the fact that the outer form 71 slopes inward toward the top and the inner form 70 slopes outward toward the top, a tapering wall 108 may be poured between the two forms with the tie rods 103, 103 holding the forms from expanding or bulging when the concrete is poured therebetween. Obviously, the uppermost tie rod 103 will be shorter than the lowest and the spacing of the holes 106, 107 from the head will vary with the length of the rods. However, in each case these rods serve the same purpose. As shown particularly in Figure 2, each section or panel of the form 71, is preferably reinforced against distortion by a pair of diagonally arranged rods 108 and 109. They are secured at the upper corners formed by upper horizontal angle member 96 and upright end angle members 98 and 99 and also at the lower corners formed by the same latter two angle members and the lower horizontal angle member 95. Thus, each section 79 of the form 71, may be made quite rigid despite considerable strain imposed thereon. The bolts 110, which secure the end angle members 98 of one section to the next adjacent angle member 99 of the following section, are removable. When the bolts are removed the sections can be separated and loaded on a truck when the entire apparatus is to be dismantled for long-dis-

tance transportation. The features of the diagonally arranged rods 108 and 109 may also be applied to the panels or form sections 72 of the inner form 70, as such construction is known in other branches of the art.

Angle members or lugs 111 and 112 are secured to the end sections of the outer form 71, one at each corner, for a purpose to be explained hereinafter. Similar angle members, not shown, are provided at the corners of the inner form 70. In addition, other angle members are arranged to be detachably secured to the forms at any desired point or points between the corner members.

It is important that the entire form be square and free of distortion so that the diagonally opposite corners will remain at accurate distances from each other and that all the angles at the corners will remain square. This is effected by an internal squaring unit, generally indicated at 113, which is disposed within the inner form 70. This squaring unit consists of four angularly disposed pairs of I-beams, as for example, beams 114, 115 secured together to form one pair; 116, 117 to form a second pair; beams 118, 119 to form a third pair; and beams 120, 121 to form a fourth pair. These corner or angular pairs are all bolted together at 122, 123, 124 and 125 to form a right-angled quadrilateral unit. At the junction in the corner between members 114 and 115 is secured a tubular radial member 126. Similarly, in the corner junction between members 116 and 117, a second tubular reinforcing member 127 is secured. In the respectively opposite corners between members 118 and 119 is fixed a rod 128 and in the remaining corner between members 120 and 121 is fixed a second rod 129. These rods 128 and 129 extend into the tubular members 126 and 127. Spaced apertures 130 extend not only through the tubular members, but also through the rods to receive pins 131 and thereby secure the whole squaring unit into a rigid form. Distortion is eliminated due to the diagonal positions of the tubular members 126 and 127 and the rods 128 and 129 connected thereto. In order to ensure the rigidity of the corners, the reinforcing plates 132 and 133, 134, 135 are bolted or otherwise detachably secured to the meeting beams 114, 115, etc., in each pair, as best seen in Figure 1.

From a description thus far, it is evident that the outer form 71 is maintained in spaced relation from the inner form 70. This is accomplished by means of the carrier bars 69, 85, 86, 87 at the corners, and also by the tie rods previously described. The tie rods provide a proper and predetermined space 136 between the two forms for pouring the concrete to form the foundation or basement wall or whatever structure is intended to be erected on the location.

Assuming that the structure thus far outlined is in readiness for pouring the concrete, the latter is then introduced between the forms until the proper level is reached and then the concrete is allowed to set until it can stand without lateral support. The foundation form is then ready to be removed from the wall and moved to another location for reuse. Pins 105 are tapped out of the tie rods 103. If necessary, the interior squaring unit 113 is removed in order to provide access to all of the tie rods within the inner form. When the pins have been removed the tie rods are all pushed outwardly and finally pulled from the outer form 71, leaving elongated holes in the concrete, as indicated at 131, 131 in Figure 4.

the wall 103 being otherwise entirely solid and smooth.

As soon as all of the tie rods have been removed, a heavy jack is placed under each of the angle members 111 and 112 on the inner form 70 and the latter is raised slightly upwardly away from the inner face of the set concrete wall. Jacks are then placed under each of the angle members on the outer form 71 and the latter is raised slightly upwardly away from the outer face of the set concrete wall. By initially raising the forms with jacks, the residual adhesion between the forms and wall is broken and the forms may then be raised by the tackles until they clear the top of the wall 103. The additional angle members arranged to be detachably secured at positions intermediate the corner members are for the purpose of being able to apply jack pressure at any point on the forms which may be adhered more tightly to the concrete than at other points. Inasmuch as the surface of the panels 94 and 101 are smooth and non-porous and in addition are inclined toward the top, they will part easily from the wall and leave a smooth finish thereon. As soon as access is had to the wall, the holes 137, 137 are filled with caulking compound and sealed at the ends with cement so that they no longer appear, as indicated at 138 and 139. The result is a wall having the two sloping sides 140, 141 with a flat top 142. The wall surfaces may then be treated to provide additional smoothness, coloring, or waterproofing, as desired. Waterproofing of the outer surface of the wall below the grade line is important and is usually accomplished by the application of an asphalt compound.

It will be observed that a tapered wall results from the use of the sloping inner and outer forms described above. Such a wall, being wider at the bottom than at the top, provides its own integral footing at the base. This is not the case of the usual wall construction. In the latter type a footing is first poured and allowed to set. Before being fully cured a wall is cast on top of the footing. As a result, the uncured footing frequently fails because of the weight imposed by the cast wall. Also, relative movement between the wall and footing sometimes results from the lateral pressure exerted by the outside earth. These objections are not experienced in the integral wall and footing obtained by the use of the device of this invention.

When viewing another portion of the concrete wall 143, as shown in Figures 7 and 8, it may be noted that a door casing 144 and a window casing 145 are accommodated in the wall so as to be incorporated therewith. In order to dispose these casings in proper position prior to pouring, they are so located that two of the highest rods 103 will pass through holes 146 in the sides of the door casing and through holes 147 in the window casing 148. The sides 149 of the door casing have tie rods passing through intermediate holes 150. The lowest tie rods are simply located beneath the base 151 of the same door casing at 152, etc. The tie rods that would normally pass through approximately the vertical central portion of the door opening and also the window opening may be omitted. Both casings are thus directly supported by tie rods and are also definitely located for the pouring of the wall. When the wall has set sufficiently, the tie rods are pulled either through or away from the casings. As the wall tapers upwardly so that it is narrowest at the top 142, the casings obviously widen toward the

bottom. It will be seen that the bottom of the door casing at 151 is wider than the top 153. Within the wall, the base layer of the floor at 154 supports the floor proper 155 which is immediately below the level of the bottom member 151 of the door frame. Although the door frame widens toward the bottom, the door jamb and other portions of the frame, will, of course, be constructed as a normal door frame which is of the same width from top to bottom.

If we now refer to the enlarged section of the side of the door frame shown in Figure 9, it is readily seen that preferably the casing 149 is longitudinally divided into two equal sections 157, 157 secured together by a concealed or reinforcing frame member 158 embedded in the wall 143. The tie rod hole 150 passes through both casing sections. The casing is divided to eliminate difficulty in obtaining a board as wide as the bottom portion of the casing. In addition, the division of the casing into the two sections allows and facilitates the trimming down to size for fitting the casing accurately to correspond to the intended size and form of wall 143.

In view of the fact that the wheel assemblages 20, 21, 22 and 23 may be steered in any direction, it is possible to roll the entire assemblage of the apparatus from one structure just completed to the next excavation, even though the latter may not be directly alongside the one just completed. It is merely necessary to tow the structure by means of a truck or tractor and to direct the wheel assemblages in the proper direction by mechanical means not shown. The assemblage is maneuvered until accurately located over the excavation to be provided with the new concrete wall, when the tower blocks 64 may again be manipulated to lower the inner and outer forms 70 and 71 into place for a new cycle of operation.

From the foregoing, it is evident that with the use of the apparatus it is possible to pour foundation walls, basement and cellar walls, and the like of various sizes. This is readily possible by merely releasing the bolts 40 holding the inner and outer channels 39, 39 on the beams 45 33, etc., of the carrier frame and then replacing the bolts 40 in new positions wherein the channel members virtually form bridges or spacing members for the longitudinal beams of the carrier frame when spaced apart various distances according to the required increase in size. When the sizes of the foundations are to be increased, additional form sections 72 and 79 are added to the sides to be lengthened of both the inner and the outer forms 70 and 71, this manipulation being so obvious as not to require specific description. In correspondence with such increase in size of the inner and outer forms, the squaring unit 113 may be correspondingly enlarged by releasing the bolts 122, 123, 124 and 50 125, and after sufficiently enlarging the unit 113 to fit the inner sides of inner form 70, these bolts may be replaced, the pins 131 being also removed from their holes 130 and replaced in new holes in the tubular members 126, 127 and rods 128, 129 to correspond to the new size of the unit 113.

Extra large wall enclosures may be formed by blocking out an end wall to form a U-shaped structure when viewed from above. A second U-shaped structure may later be poured in abutment so that the open ends of both are in alignment. This would effect an enclosure approximately twice the length of a completed wall formed normally by use of the inner and outer

forms. It is readily apparent that the open-ended enclosures may also abut at any desired angle.

It will be noted that the foundation form described above provides inner and outer forms which may singly or together be raised and lowered by the chain hoists carried by the carrier frame. When the forms are resting within an excavation it is possible to raise one relative to the other a sufficient height to expose the sloping casting surfaces to cleaning operations and for the unrestricted positioning of door and window frames and tie rods. If desired, reinforcing rods for the concrete may also be positioned at this time. When only one of the forms is to be raised, the carrier bar 69 is disconnected from the other form.

In the form of the apparatus already outlined, tie rods are used to hold the inner and outer forms properly and evenly spaced apart and to prevent the same from expanding individually at any point when the concrete is poured between the two forms. In addition to being secured by the tie rods, both forms are secured together at the corners by means of the radially disposed carrier bars connected to the tackle supported by the corner towers. However, in Figures 12 to 14, are shown means for avoiding the use of tie rods passing directly through the space between the forms and through the wall poured between said forms.

The carrier frame in this form of construction includes overlapping channel members 159, 160 at each side. A similar arrangement of channel members, of which only the portions 161, 162 are shown, is provided at the ends. The side and end channel members are secured at right angles by means of angle plates 163, in the same manner as angle plates 27, 28 were described as being secured to beams 25 and 26. In order to allow for expansion or reduction in size for various sizes of foundations, bolts 164 may be temporarily removed and holes 165, 166 shifted further apart or closer together until they register and the bolts replaced according to the size required. This construction is the same for all four sides of the carrier frame, which, in this case, is generally indicated at 167.

At the corners of the frame, that is, at the ends of the beams 161 and 162, etc., are channels 168 and 169 reinforcing the extensions 170 and 171. A wheel assembly may be mounted at each corner as already described in connection with carrier frames 15 in Figures 1 and 2 which require no further description here, inasmuch as the construction is well understood and, of course, holds in equal manner for the present frame. At each corner, as for example upon the beams 159 and 161, are erected a pair of posts 172 and 173. These posts are surmounted by a horizontal top member or tackle beam 174 reinforced by diagonal bars 175 and 176. The posts 172 and 173 are further secured in erect position by the inclined angle beams 177 and 178 which are detachably secured at their upper ends to the posts and at their lower ends to the upper part of channels 161 and 168. At the junction of the channel members 159 and 161, forming the corner, an angle plate 179 is preferably bolted or otherwise detachably secured to the members 177 and 178 and further secured to the channel members 159 and 161 to form a firm anchorage for the tower. From the upper beam 174 of the tower is suspended the tackle block 183 in conventional manner with the tackle chain 181 hav-

ing the lower hook 182 thereof engaging with the suspension eye 183 upon a loose carrier bar 184 from which both the inner form 185 and the outer form 186 are suspended. For effecting this suspension, the upper edge of form 185 is provided with two bridge members 187 and 188. The upper edges of form 186, that is, the outer form, are similarly provided with bridge members 189 and 190. Beneath the four bridge members, the carrier bar 184 projects at both ends thereof in slidable manner so that maneuvering of either form is possible independently of the other. Freedom of movement is possible because of the fact that the carrier bar 184 is not definitely secured to either form, but merely holds the same in suspension. The bridge members may be secured to the upper edges of the forms by means of bolts or the like, or by any other means known in the art, as such means form no part of the present invention as such.

Inasmuch as no ties or tie rods are used in the present form of the apparatus to pass directly through the wall to be poured, a special supporting tie structure is provided. The panels or sections of the forms illustrated are entirely like those already described in Figures 1 and 2. As Figure 12 is merely a fragmentary view of the entire carrier frame with its appurtenances and inner and outer forms, there are shown only portions of the latter and but one of the tie structures. In actual operation, as many tie structures are provided as will be required to effect the same results as with the use of tie rods.

The tie structure of this modified form of construction, which eliminates the need of the rods, is shown in detail in Figure 13. The angle members 191 and 192 of the inner and outer forms make up the panel sections having facing panels 193 and 194 between which a wall 195 is cast. These are similar in construction to the panel sections described previously in the forms shown in Figures 1 and 2. At the bottom ends of angle members 191 and 192 are secured horizontal angle members 196 and 197 and at their upper ends are secured angle members 198 and 199. A pair of upwardly extending and outwardly inclined tie members 200 and 201 are connected at their lower ends to the lower portions of angle members 191 and 192 of the forms by means of pivots 202 and 203. Their upper ends are connected by means of pivots 205 and 206 to a horizontal angle member 204 which is considerably longer than the width of the base of wall 195. This horizontal angle member is attached to the upper ends of the horizontal angle members 198 and 199 by means of anchor members shown as bolts 207 and 208. The resulting structure maintains the upper and lower portions of forms 185 and 186 spaced apart at the predetermined angles and distances intended to constitute the dimensions of wall 195 when poured between the forms. It is evident that the tie structure so provided in no way penetrates the wall 195 poured between the forms so that the panels 193, 194 of said forms may be entirely imperforate and smooth on the inner sides facing the wall. It is evident that, due to the triangular construction which results between the upright 192, the outer tie member 201, and one end of the upper horizontal member 204, the lower end of the form will be prevented from shifting either inwardly or outwardly. The same is true of the lower end of form 185 due to the triangular structure which

results when the outer tie member 200 is secured at the lower end to the upright 191 and the latter, as well as tie member 200, are secured to the other end portion of the upper horizontal member 204.

When the wall has set sufficiently to stand without support, the forms 185 and 186 are released by removing the bolts 207 and 208. This permits the structures to pivot about the points 205 and 206. The inner and outer forms are then stripped from the cast wall in the same manner as previously described.

From the foregoing, it is evident that in the different constructions shown in Figures 1 and 12 substantially the same principles hold.

While the pouring forms and carrier frames have been specifically detailed herein, it is within the purview of my invention to have forms and carrier frames with any number of sides. Thus in the following claim, the number of corner sections and frame sides set forth should be interpreted as meaning any desired plurality not limited to the form or number specified.

The carrier frame may be completely detached from the inner and outer forms when the concrete has been poured, and may be towed to a new site or excavation and furnished with a second pair of forms and concrete poured therein. This separation of the carrier frame from the forms may be done as often either as unused forms are available or as forms are ready to be stripped and reused.

While several embodiments of the present invention have been shown herein, it will of course be understood that the invention is not to be

limited thereto since many modifications may be made.

I claim as my invention:

A structure for forming a wall of cementitious material or the like comprising nested quadrilateral shaped forms having a space therebetween for receiving the wall forming material, a pair of bridge members on each form individually secured to an upper edge thereof in spaced relation from a corner, the arrangement being such that a pair of bridge members is provided on each side of the corner and each form supports one of the pair of members, and a carrier bar extending across adjacent form corners with the ends being selectively projected through said bridge members either to engage the bridge members of one form or both simultaneously.

RICHARD R. VON BAMPUS.
